UNITED STATES PATENT OFFICE.

ABRAHAM FINN, OF ELIZABETH, NEW JERSEY.

PAPER-HANGER'S TABLE.

Application filed December 17, 1921. Serial No. 523,104.

To all whom it may concern:

Be it known that I, ABRAHAM FINN, residing at Elizabeth, in the county of Union and State of New Jersey, have invented new and useful Improvements in Paper-Hangers' Tables, of which the following is a specification.

This invention relates to paper hangers' tables, and one of the objects is to produce 10 a device of this nature which is collapsible so that it may be carried in an ordinary suit case.

Another object is to produce a table of this kind which shall be more perfectly adapted 15 for the use to which it is put than are the tables at present on the market.

Another object is to provide a table of this nature in which the structure shall be made by all short pieces of wood so as to avoid 20 as far as possible the tendency to warp and bend.

Another object is to produce a device of 25 this nature which shall be provided with replaceable cutting boards for use with a knife, and with a metal cutting strip for use with rollers or machine cutters.

Another object is to provide a table of this nature with readily foldable legs which shall be so placed so as to counteract each 30 other when the table is in use and prevent tendency to shake or rattle.

Another object is to provide a device of 35 this nature which shall be simple of construction, cheap to manufacture, and highly efficient for the purpose for which it is designed.

With these and other objects in view, the invention resides in certain novel construction, and combination and arrangement of 40 parts, the essential features of which are hereinafter fully described, are particularly pointed out in the appended claims, and are illustrated in the accompanying drawing, in which:—

Figure 1 is a side elevation of the table.

Figure 2, is a top plan view of the same, parts being broken away for the sake of clearness.

Figure 3, is an end view of the same.

Figure 4, is a vertical transverse sectional view of the same on line 4—4 of Figure 1.

Figure 5, is a detail view of the leg securing means.

Figure 6, is a fragmentary perspective 55 view of the joint of one of the corner legs.

Figure 7, is a perspective view of the securing tenon of one of the legs.

Figure 8, is a view of the straight edge.

Figure 9, is an edge view of the same.

Figure 10, is a sectional view on line 60 10—10 of Figure 8 showing the means for securing the sections together.

Like characters of reference refer to like parts in all views.

Referring to the drawing in detail, the main structure of the table comprises three sections A, B and C, of which, sections A and B are hinged together as at 10. Each of these sections A, B and C comprises side boards 11 and 12 between which there is secured a canvas strip 13. Long rods 14 having thumb pieces 15, have their shanks extending through bearings formed in the side board 11 and the inner end of the shank rests against a metal bearing block 16 in the side board 12. Each of the rods 14 is provided with a threaded portion 17 which co-acts with a correspondingly threaded block 18 secured near the inner edge of the side board 11. It will be readily understood 70 that when the rod 14 is inserted and the threaded portion 17 is screwed into the portion 18, the members 11 and 12 will be forced apart thereby stretching the canvas strip 13.

Members B and C are secured together by iron strips 19, fastened to the sides of member C and provided with apertures to register with dowels 20 on the section B. There are also provided plates 21 which are 90 screwed to the member C and fit in the mortised out parts in the members 11 and 12 of section B. Portions of the legs which are presently to be described pass through the members 21 so as to lock them in place, and are themselves locked in position by means of the rod 14 at this point which passes through the strip 19 and through the portion of the leg.

The table is provided with eight legs of 100 which four are straight when extended and are hingedly attached at four corners of the table. These four legs comprise outer members 23 which are as above mentioned hingedly connected at the respective corners of the table and have their depending ends pivotally connected to the bottom members 24 as at 24'. U-shaped bales 25 on the members 24 are attached to embrace the respective members 23 so as to lock the leg members 105 110

in extended condition, movement of the bale member 25 being limited by a stop pin or lock 26 on member 23.

The other four legs are of X-formation and each comprises two upper members 27 and two lower members 28, the four being pivotally connected at 29. Each of the upper members 27 is provided with a metal extension 30 which extends into a socket in the respective member 11 or 12 in which it is adapted to fit. Each pair of members 28 is provided with a strut 31 having its opposite ends secured to the members 28 and hinged in its middle at 32 so that the members 28 may be folded together by bending the hinge in member 31. The strut will hold the members 28 in proper position when spread apart.

Two of the X legs are secured to the section B and are arranged lengthwise of the table, their extensions 30 being provided with apertures through which the respective rods 14 pass as above generally described. The other two X legs are arranged cross-wise of the table and each one is secured in a respective one of the sections A and C. From this construction it will be seen that while the lower portions of the X legs are free to swing when the table is picked up, they form a substantial means for supporting the table when in working condition, and with the arrangement of two of the legs longitudinally and the other two transversely of the table prevents any tendency to wobble or to be unsteady which might result from the legs being constructed in pivoted sections.

The X legs are secured to the boards 11 and 12 sufficiently inwardly, so that the legs 23—24 may be folded along the members 11 and 12 when it is desired to carry the device as through the door from one room into another. The foldable quality of all the legs greatly increases the value of the table in this respect, as the structure may be readily moved from one room to another without disassembling, and without injury to either the wood work or the table.

The upper portion of the canvas 13 is slotted at 34 so as to give a hand hold, the slots 34 being arranged in alignment with the end bars 14, so that the operator may grasp these bars for a sure means by which to move the table from place to place. Slats 35 are placed in slips or ways in the canvas covering, and when the table is in extended condition, they may be projected from their respective sections A, B and C so as to overlap the adjacent rod 14, this gives a firm 60 and a very true surface to the table.

The members 11 are cut at their upper surface so as to provide recesses for receiving removable cutting sections 36. The edge of the wall paper has to be cut and removed, 65 and the ordinary paper hangers' table very

soon becomes useless from the number of ridges made in its surface by the repeated cutting with a knife of the edges of the paper. This usually necessitates the removal of an entire board with considerable labor and expense in the replacement. The boards 36 of the present invention may be readily removed and thrown away when they become useless, and now portions can be inserted with no labor and at comparatively very small expense.

Along the members 13' there is provided a metal strip 36 which is used when the operator utilizes a roller or cutting machine in place of an ordinary knife.

Some papers, and this refers particularly to the more expensive papers, have no margin line marked on their edges, indicating where the paper should be cut and it is then necessary to use a roller or some such means for measuring. To obviate this I provide an extra board, which normally rests upon the extending portions of the end members 14 so as to form an extension of the table, and so is provided both with a straight edge for guiding the knife in cutting and with a means for measuring the distance at which the cutting is being done.

This straight edge comprises three sections 38, 39 and 40. The members 38 and 40 being provided with metal plates 41 which extend over plates 42 of member 39 and have apertures which co-act with dowels thereon. Also plates 43 secured in member 38 and 40 extend into mortices in member 39 whereby the three parts are securely joined together.

The longitudinal edge of the three members is provided with a metallic strip 44, and in the free ends of members 38 and 40 there are provided slides 45 to one of which a wire 46 is permanently secured. The other end of the wire is secured to a member 47 which is provided with screw threads co-operative with a thumb nut 48. The screw member 47 passes through an aperture in block 49 secured to one of the members 45. Upon manipulation of the adjacent thumb nut the tautness of the wire will bring the metallic edges of the three members into desired alignment for use as a straight edge. Members 45 are provided with scale markings so as to indicate the distance of the wire from the straight edge, and by adjusting members 45 and their slots or mortices, any desired amount of edge may be accurately measured and quickly removed from the paper.

While I have described what I deem to be the most desirable embodiment of my invention, it is obvious that many of the details of construction may be varied without in any way departing from the spirit of my invention, and I therefore do not limit myself to the exact details of construction herein set forth nor to anything less than the whole

of my invention limited only by the appended claims.

What is claimed as new is:—

1. A table of the class described comprising a collapsible top having flexible elements and means for stretching the same, a metal cutting strip on one side of said table, and a removable sectional cutting strip on the other side of said table.
- 10 2. A table of the class described comprising a collapsible top having canvas elements and means for stretching the same, a metal cutting strip on one side of said table, a removable sectional wooden cutting strip on the other side of said table, and a foldable straight edge device comprising adjustable means for measuring the edge of paper, and normally co-operative with as an extension of said table.
- 20 3. A table comprising a flexible top, means for stretching said top, a plurality of legs of X-formation secured thereto, and a plurality of straight legs hingedly secured to said top at the corners of said top.
- 25 4. A device of the class described having a top including a canvas element, means for stretching said canvas element, and legs secured to said table by the said means.
5. A table of the class described comprising a top including a fabric element, means for stretching said fabric element, and foldable legs secured to said top by said stretching means. 30
6. A table of the class described comprising a top constructed in sections, certain of said sections being hingedly connected and other of said sections being detachably connected; means for adjusting said top transversely, slidably connected means in said top, a plurality of foldable X-legs secured to said top by the first said means, a plurality of X legs co-operative with the said top and arranged at right angles to the first said legs, and a plurality of said legs hingedly connected to said top at the corners thereof. 35 40 45
7. A table of the class described comprising a plurality of foldable top sections, means for stretching said sections, and a plurality of pivotally jointed legs hingedly secured to said top, at the corners thereof, 50 and means on each of said legs for securing said legs in extended condition.

In testimony whereof I have affixed my signature.

ABRAHAM FINN.
